HAIR WAVING OR CURLING DEVICE

Stephen B. Beliaeff, Malverne, N. Y.

Application August 22, 1935, Serial No. 37,323

9 Claims. (Cl. 132—41)

This invention relates to improvements in hair waving or curling devices. It relates particularly to the type of hair curling devices provided with means for gripping the hair ends which are then rolled in a number of convolutions to form a curl, and further provided with a clamp to hold the hair in its curled condition after the completion of the rolling operation.

An object of the present invention is to provide a device of the character described of greatly simplified construction, whereby the members may be readily and quickly assembled, which will be economical to manufacture and at the same time operate with a high degree of efficiency for the purposes intended.

Another object of my invention is to provide a device of the character described having improved clamping means.

Still another object of my invention is to provide a device of the character described having novel clamp attaching means.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible embodiments of this invention,

Fig. 1 is a plan view of a hair curling device embodying my invention;

Fig. 2 is a side view, partly sectional, of the Fig. 1 form of device;

Fig. 3 is an end view, partly sectional, of the Fig. 1 form of device;

Fig. 4 is a view in section taken substantially on the line 4—4 of Fig. 2;

Fig. 5 is an enlarged detail, partly sectional, of a portion of the device illustrated in Fig. 2;

Fig. 6 is a view similar to Fig. 5;

Fig. 7 is a view partly sectional, of a portion of the Fig. 1 form of device, but illustrating a modified form of clamp;

Referring now in detail to the drawing, there is disclosed in Figs. 1 to 6 a hair curling device embodying the various features of my invention, said device comprising a hair rolling element 20 which may be of hollow tubular construction and provided with a suitable hair gripping member 21 pivotally connected to the rolling element 20 by a novel connecting means to be described in greater detail as the description proceeds. The

gripping member 21 and the rolling element 20 are each provided with similarly designed extensions or finger pieces 22 and 23, respectively, adapted to have received between them a leaf spring member 25 designed to normally spread said finger pieces apart to urge the gripping member 21 into pressing engagement with the rolling element 20.

When it is desired to roll the hair into one or more convolutions to form a curl, the finger pieces 22 and 23 are compressed against the action of the spring 25 to raise the gripping member 21 to the dotted line or ineffective position 26, as shown in Fig. 2 of the drawing. The ends of the hair are then placed on the rolling element and the finger pieces 22 and 23 released to allow the member 21 to grip the hair to hold the same against the element 20. The hair is then rolled or coiled on said element 20. After this has been done it is necessary to provide means for binding and maintaining the hair in place.

By my invention I have provided a novel binding member which at the same time serves to pivotally connect the gripping member 21 to the rolling element 20. The means by which this is accomplished may be described as follows:

There is disclosed in Figs. 1 to 3 of the drawing a suitable hair clamp 30 which may be of the bail type, as shown, having portions extending along the rolling element 20 and around the end 30 thereof, the open ends being pivotally engaged in the element 20 and the member 21 in the following manner:

It will be noted that the members 20 and 21 are each provided with a pair of overlapping ears 31, 31' adjacent the finger pieces 22 and 23. Said ears 31 are provided with aligned annular apertures 35 of a size slightly larger than the cross-section of said clamp 30 and adapted to receive a portion adjacent the ends 32 for free rotation 40 therein.

Similarly the ears 31' are provided with aligned annular apertures 35' of a size slightly larger than the cross-section of said clamp 30 and adapted to receive a portion adjacent the end 32' for free rotation therein. The ends 32 and 32' are provided with flattened and flared portions 36, 36' of a width greater than the diameter of the apertures 35, 35'. It will be noted that the said apertures 35, 35' are provided with 50 horizontally extending slotted portions of slightly greater width than the thickness of the flattened portions 36, 36' and of lesser width than the diameter of the apertures 35, 35'.

The construction as described above is so de- 55

signed as to permit the ends 32, 32' of the portion adjacent the clamp 30 to be inserted into the apertures 35, 35', to pivotally connect the gripping member 21 to the rolling element 20, 5 only when said clamp is in a position which is substantially at right angles to the said members 20 and 21. When the clamp 30 has thus been pivotally mounted, it is rotated to a position as shown by the dotted lines in Fig. 1 of 10 the drawing, which is the operative position for rolling or curling the hair, or it may be rotated to the full line position which is the operative position for clamping the rolled hair to retain the same in rolled condition.

15 By the construction as described, it is also seen that the ends 32, 32' will be retained in position within the apertures 35, 35' until it is desired to disassemble the device, at which time it is necessary to position the clamp 30 at right 20 angles to the rolling element 20 and withdraw the ends 32, 32'.

Any suitable means may be employed for locking the clamp 30 in position, such as a pair of aligned circumferential notches 40 in the outer 25 end of the rolling element 20, adapted to receive the closed end portion of the clamp 30. Due to the resilient construction of the clamp 30 it may be designed to snap into position and held in the notches 40.

30 In Fig. 7 of the drawing there is disclosed a modified form of clamp 41 pivotally mounted in the same manner as the clamp 30 but having its closed end portion extended beyond the length of the rolling element 20 and looped to form a 35 handle 42 to facilitate the locking and unlocking of said clamp 41 from the notches 40.

In using hair curling devices of the character described, it is the customary practice to treat or wet the hair with some solution before winding 40 said hair on the rolling member. Since the rolling operation is performed by hand, the fingers of the operator must of necessity become moist from handling the moist hair. Due to this fact it is oftentimes difficult to obtain a good 45 grip on the curling device due to the fact that the moisture tends to allow the curling device to slip out of the fingers. To overcome this disadvantage, I have provided suitable means on the finger pieces 22 and 23 to prevent slipping 50 when in use. In Figs. 1, 2, 5, 6 of the drawing there is shown one such means which comprises a plurality of perforations 64 suitably positioned in the finger pieces 22 and 23.

It will thus be seen that there is provided a 55 device in which the several objects of this invention are achieved, and which is well adapted to meet the conditions of practical use.

As various possible embodiments might be made of the above invention, and as various 60 changes might be made in the embodiment above set forth, it is to be understood that all matter herein set forth or shown in the accompanying drawing is to be interpreted as illustrative and not in a limiting sense.

65 Having thus described my invention, I claim as new and desire to secure by Letters Patent:

1. A device of the character described, comprising a tubular member adapted to have hair rolled thereon, a second member cooperating with 70 said tubular member, and clamping means for holding the roll of hair in place, said last named means comprising a wire member having deformed ends, adapted to pass through mating means cut through the walls of both of said 75 members for pivotally mounting said second

member on said tubular member, said deformed ends being withdrawable through said mating means only upon aligning said deformed ends with said mating means, to disassemble said device. 5

2. A device of the character described, comprising a tubular member adapted to have hair rolled thereon, a second member cooperating with said tubular member, resilient means between the members to urge said second member into pressing engagement with said tubular member to grip the hair preparatory to rolling the same, and clamping means for holding the roll of hair in place, said last named means comprising a wire member having deformed ends, 10 adapted to pass through mating means cut through the walls of both of said members for pivotally mounting said second member on said tubular member, said wire member ends being deformed before assembly of said device. 15

3. A device of the character described comprising means adapted to have hair rolled thereon, means for gripping the hair preparatory to rolling, and means for holding the rolled hair in place, said last named means comprising a wire 25 member having deformed ends, adapted to pass through mating means cut through the walls of said hair gripping and said hair rolling means for pivotally mounting said hair gripping means on said hair rolling means, said deformed ends 30 being withdrawable through said mating means only upon aligning said deformed ends with said mating means, to disassemble said device.

4. A device of the character described comprising a member adapted to have hair rolled 35 thereon, a second member adapted to grip the hair preparatory to rolling, said members having pairs of overlapping ears between the ends thereof provided with aligned apertures therein, and means for holding the rolled hair in place, 40 said last named means comprising a loop of wire-like material, each end of said loop being deformed and adapted to pass through mating means cut through said overlapping ears to pivotally connect the said members, said deformed 45 ends being withdrawable through said mating means only upon aligning said deformed ends with said mating means, to disassemble said device.

5. A device of the character described comprising a member adapted to have hair rolled thereon, a second member adapted to grip the hair preparatory to rolling, said members having pairs of overlapping ears between the ends thereof provided with aligned annular apertures 55 therein, each of said apertures having a horizontal slot of greater length than the diameter of said aperture and disposed substantially across the center thereof, and means for holding the rolled hair in place, said last named means comprising a loop of wire of substantially annular cross-section, each end of said wire being flattened to pass through said aligned apertures to pivotally connect the said members, the said flattened ends preventing disengagement of said 60 wire from said apertures except when said flattened ends are in mating alignment with said horizontal slots.

6. A device of the character described comprising a member adapted to have hair rolled 70 thereon, a second member adapted to grip the hair preparatory to rolling, said members having pairs of overlapping ears between the ends thereof, said first named member having notches 75 in the end thereof most remote from said ears

and means for holding the rolled hair in place, said last named means comprising a clamping bail having a looped end adapted to cooperate with said notches and the free ends being deformed and adapted to be received in mating apertures in said overlapping ears to pivotally connect the said members.

7. A device of the character described comprising a member adapted to have hair rolled thereon, a second member adapted to grip the hair preparatory to rolling, said members having pairs of overlapping ears between the ends thereof, said first named member having notches in the end thereof most remote from said ears and means for holding the rolled hair in place, said last named means comprising a clamping bail having a looped end adapted to extend beyond said hair rolling member when caused to engage said notches, to form a handle for said clamping bail, the free ends of said bail being deformed and adapted to be inserted through mating apertures in said overlapping ears to pivotally connect the said members.

8. A device of the character described comprising a tubular member adapted to have hair rolled thereon, a second member adapted to grip the hair preparatory to rolling, each of said members having finger grip portions at one end thereof provided with means to prevent slipping

when said portions are contacted by the fingers of the operator, and means for holding the rolled hair in said rolled condition, said last named means including means integral therewith for pivotally interconnecting said members, said last named integral means comprising a wire member having deformed ends and adapted to pass through mating apertures in said tubular and said second members.

9. A device of the character described comprising a member adapted to have hair rolled thereon, a second member adapted to grip the hair preparatory to rolling, said members having pairs of overlapping ears between the ends thereof, each of said apertures having a horizontal slot of greater length than the diameter of said aperture and disposed substantially across the center thereof, and means for holding the rolled hair in place, said last named means comprising a loop of wire of substantially annular cross-section, each end of said wire being flattened to pass through said aligned apertures to pivotally connect the said members, the said flattened ends preventing disengagement of said wire from said apertures except when said flattened ends are in mating alignment with said horizontal slots, said flattened ends being disposed in spaced relationship to each other.
